ABSTRACT OF THE DISCLOSURE

A pair of flexible support members positioned exterior of and parallel to a plating zone defined by the cathodic workpiece and a conforming, closely-spaced pressure member are utilized to move a multiplicity of partially-overlapping porous, resilient hard particle-carrying activator sheet materials through such plating zone in contact with the surfaces of the workpiece receiving the plate throughout the period of imposed current flow.

FIELD OF THE INVENTION

The present apparatus is used in the field of electro-deposition and more specifically as a means to practice the process disclosed and claimed in U.S. Letters Patent No. 3,619,384, issued on Nov. 9, 1971 to Steve Eisner and entitled "Electrodeposition." Such process is herein-after referred to as the "N-E-T I" process for convenience of description. In particular, the present apparatus is designed to permit the practice of such process on the plating of interior and/or exterior surfaces of workpieces having curved or contoured configurations such that any point on the surface to be plated a straight line can be drawn from one side to the other on such surface and remain in a single plane. Typical examples of such workpieces are cylinders or an epi-trichoid such as the interior of the housing of the rotary combustion engine commonly identified as the "Wankel" engine.

PRIOR ART

The aforesaid process patent, No. 3,619,384, and a series of related patents issued on the same date to the same patentee, Nos. 3,619,401, 3,619,383 and 3,619,400 are believed to be the closest prior art. A copending application of Steve Eisner, Ser. No. 102,287 entitled "Vibratory Process" and filed on Dec. 29, 1970, now U.S. Pat. No. 3,699,014 illustrates another approach to the problem met by the apparatus of the present invention.

SUMMARY OF THE INVENTION

In the N-E-T I process, a plurality of small, hard activating particles supported in fixed relationship to one another on at least the surface of a porous, flexible, resilient, supporting matrix, are moved over the surface of an electrodeposit as it forms throughout the period of electro-deposition. The repetitive particle contacts at very short time intervals mechanically activate the deposit surface, drastically increasing the rate at which metal in a sound, coherent form can be deposited on such surface. The process either takes place below the surface of the electrolyte or electrolyte is flooded into the plating zone at a high rate to provide the requisite supply of metal ions.

Apparatus for practicing this process is disclosed and claimed in the aforementioned U.S. Letters Patent No. 3,619,401 while apparatus specific to depositing plate on flat strip is disclosed and claimed in the aforementioned U.S. Letters Patent No. 3,619,383. Both of these illustrate the process as applied to flat stock such as strip or to mildly-contoured items such as rolls. The aforementioned copending application, Ser. No. 102,287 illustrates what can be termed "shaped wheels" as one way of applying the particle-carrying activator material to two-dimension-

2

ally contoured shapes such as bumpers or the like. The present invention is an improved apparatus for operating on two-dimensionally curved surfaces and essentially consists of a pair of spaced, flexible support members maintained essentially parallel with one another at any given point in the length of such members. Disposed between such flexible support members and affixed thereto by engagement with generally rigid cross-connecting members extending between the flexible members are a number of sheets or flaps made of suitable activating materials. As described in the aforementioned patents, such activator materials are preferably porous, compressible and resilient webs, usually formed from fibers chemically resistant to the plating solutions with which the material is to be used and anchored one to the other in a nonwoven form. Woven, non-porous materials can be used as described in such patents but are not preferred. Affixed to at least the work-contacting surface of such webs and anchored thereto by a suitable chemically-resistant adhesive in spaced relationship one to another are a plurality of small, hard activating particles, usually, but not necessarily, abrasive grains. The description of such materials is believed sufficiently complete above but the disclosure thereof contained in the aforementioned U.S. Letters Patent are incorporated herein by reference for sake of completeness. Generally such activator materials have been illustrated in the foregoing patents in the form of belts, discs, wheels or the like capable of moving over the surface being plated or in the form of static sheets over which the surface to be plated is moved as more specifically described and claimed in the copending application Ser. No. 256,884 of Steve Eisner, entitled "Plating Apparatus" and filed on May 25, 1972. Here, as aforesaid, such material is provided in the form of a plurality of sheets, usually rectangular in shape, which are interposed between and supported by the parallel, flexible spaced support members. This structure is inserted into a plating system where the interior or exterior surface of a two-dimensionally curved workpiece is to be plated. As part of the apparatus, a pressure-plate closely conforming to the contours to be plated of the workpiece is provided and positioned in close proximity to such contours on the workpiece. The workpiece and this pressure plate define the plating zone and usually and preferably, the pressure plate serves double-duty as the inert anode in the system. In all cases, such pressure plate is perforated at frequent intervals over its entire surface to permit ready electrolyte flow therethrough. Where the plate is made of plastic or the like, anodes are placed adjacent its perforated outer surface. The flaps or sheets of activator material are interposed in the plating zone defined by the workpiece and the pressure plate with the flexible support members outside such zone and on each side thereof. For purposes of convenience, such positioning of the support members relative to the plating zone is generally hereinafter referred to as being "outboard" of such zone. The flaps of material are preferably so spaced that the end of one flap overlaps the start of the next when the flaps are confined within the plating zone. The outboard support members run parallel with the contours of the plating zone and with each other. Means are provided to drive these outboard support members, which are preferably and usually in the form of endless loops, so as to pull the overlapping flaps through the plating zone defined by the workpiece surface and the conforming pressure plate. As is illustrated in the drawings discussed below, coverage of quite complex contours can easily be achieved with this apparatus arrangement.

DRAWINGS

FIG. 1 is a schematic illustration of one form of the support members and associated cross-connecting mem-

bers here shown without the activator materials for purposes of clarity in illustration.

FIG. 2 is a cross-sectional view long the line 2—2 of FIG. 1 with the activator flaps inserted.

FIG. 3 illustrates schematically a different form of support member and connecting member arranged according to the present invention (and again shown without the activator flaps for clarity).

FIG. 4 is a schematic end view of a part set up in a plating tank for internal surface plating as is shown in more detail in FIG. 5.

FIG. 5 is a cross-sectional view taken on line 5—5 of FIG. 4 of a contoured workpiece set up for interior surface plating in accordance with the present invention.

FIG. 6 is a schematic illustration of the plating of a portion of the exterior surface of a rotating cylinder with apparatus of the present invention.

DESCRIPTION OF PREFERRED EMBODIMENTS

Referring now to the drawings, FIGS. 1-3 illustrate several types of support structures which may be used as components of the present apparatus. With reference to FIG. 1, the support structure 10 consists of a pair of parallel, spaced, flexible support members 11 (here shown as hollow plastic tubing) connected to each other by sets of cross-connecting members 12, each of which has a bent end 13 which, when inserted into holes in support members 11, prevents the accidental dislodgment of member 12 therefrom. Spring clips 14 are slipped over the ends of each set of cross-connecting members 12 to urge them toward each other to provide for positive locking in place of the sheets or flaps of activator material held between the cross-members 12 in use as shown in FIG. 2.

In FIG. 2, the support structure 10 of FIG. 1 is shown with the activator flaps 15 in place on cross-connecting members 12. As illustrated, each activator section 15 is inserted between the respective sets of pins or cross-members 12 so that the upper end 18 (which will contact the workpiece in usage) of such activator flap 15 overlaps or essentially overlaps the next section 15 forming an essentially continuous surface of activator material. These ends may be tapered if desired to provide better uniformity of contact but generally, due to the resilient nature of the activator material 16, such tapering is not necessary. As shown, at least the outer surface of each flap 15 supports a plurality of small, hard, spaced, activating particles 17 secured thereto by a suitable adhesive (not shown). In operation, all activating units are moved in the direction of the closed end of the flaps as indicated by the arrow.

FIG. 3 illustrates a schematic view of a slightly different type of support structure. Here, a pair of flat, flexible plastic strips 30 are the parallel support members, each containing a continuous line of recessed openings 31 designed to mate with drive teeth on the driving mechanism (not shown). The cross-connecting member 32 here is a single pin 33 for each flap having a cut-out central portion 34 through which the flap member is inserted. Each end of pin 33 is also cut out or notched as shown at 35 to allow the pin 33 to fit over the flat support members 30. A rivet 36 fastens the split ends of pin 33 to the support members 30.

FIGS. 4 and 5 show apparatus of the present invention set up in a plating tank to plate the interior surfaces of a rotary engine combustion chamber. The workpiece 40 is shown in FIG. 4 immersed in the plating electrolyte 41. Suitable electrical connections make at least the interior surfaces of workpiece 40 cathodic. The parallel, flexible support members 42 are shown outboard of workpiece 40 with the cross-connecting members 43 extending through from one side to the other of said workpiece 40. The support members are driven over drive pulleys 44 mounted on shafts 45 by suitable means (not illustrated).

In FIG. 5, a cross section taken on line 5—5 of FIG. 4 illustrates the way the apparatus functions. Here, the

workpiece 40 immersed in the electrolyte 41 is shown as having an epi-trochoid shaped opening 50. Typical dimensions for such an opening are 11 inches in the vertical direction by 8 inches in the width direction by 3 inches in depth. While here illustrated as set up for plating a single unit in practice, multiples of 3 to 8 workpieces would usually be assembled and the plating carried out on all of these at the same time using activator flaps of the appropriate width. The inside surfaces 51 of the opening 50 are to be plated (usually with hard chrome). A conforming inert (lead) anode 52 is provided, closely spaced from such surfaces 51. A plurality of perforations 53 in the inert, conforming anode 52 permit electrolyte 41 to circulate freely through the anode and into the plating zone defined by such anode 52 and the workpiece surfaces 51. Support structures such as 54 are usually required to maintain dimensional stability for anodes of this kind but can be varied or dispensed with as desired. As shown, a plurality of flaps 55 of activator material such as has been described above are fastened to the connecting members 43. Rotation of the outboard support members 42 (see FIG. 4) in the direction shown by the arrows on FIG. 5 causes the hard particles carried by flaps 55 to activate the surfaces 51 producing increased deposition rates in accordance with the N-E-T I process.

FIG. 6 schematically illustrates a modified version of the apparatus here used to plate a section of a cylinder 60 which is rotated as shown by the arrow into plating electrolyte 61 so that the entire surface of cylinder 60 can be plated. This type of operation could be performed by a continuous belt of activator material but, as is pointed out below, the present structure even here has some distinct advantages over the belt approach. Here the flexible outboard support members are shown at 62 being driven over pulleys 63 by suitable drive means (not shown). A plurality of flaps 64 of activator material are positioned over and locked between the cross-connecting pins 62' and are pulled through a plating zone defined by the surface of cylinder 60 and a perforated, plastic pressure plate 65 having a plurality of openings or perforations 66 therethrough to permit the electrolyte 61 to readily flow into such plating zone. Beneath and adjacent the pressure plate 65 are a plurality of soluble anode bars 67 supported on rack 68. Cathode contactor 69 is shown riding against the surface of the rotating roll 60. As shown in this view, the flaps 64 hang loosely from the cross-connecting pins 62' except where they move into and are confined by the walls of the plating zone, i.e. by the surface of roll 60 and the upper face of conforming pressure plate 65. The gap of the plating zone is set so as to slightly compress the material of the flaps 64. This will give a pressure of between about 0.01 to 0.3 pound/in.² depending upon the specific construction of the activator material used. This pressure range appears satisfactory for N-E-T I plating of most metals. Hard chrome can tolerate much higher pressures without producing undesirable properties in the deposited metal or any significant wearing away of the plate. Speeds of movement of the flaps across the surface to be plated will generally range from about 100 surface feet/minute up to about 1000 surface feet/minute with usual speeds in the range of 200 to 400 surface feet/minute. Rotation of the cylinder 60 counter to direction of travel of the flaps 64 (as illustrated) permits obtaining this relative motion without excessive speed requirement of the flap units 64, e.g. the cylinder can be rotated at several hundred surface feet per minute itself.

Apparatus of the type herein described and claimed possesses a number of advantages over the belt units illustrated in some of the aforementioned patents. It not only can be used for convolute surfaces which a belt could not cover or could cover only with very complex drive mechanisms, but it permits of replacement of sections in the event of undue wear at any point whereas a belt must be completely replaced if a portion of it fails. Further, closer gap settings can be maintained since all drive members

are outside of the plating zone defined by the gap. An extremely important feature of this construction is that the width of the activator material is limited only by the needed rigidity of the cross-connecting members. Belts are generally limited by the need to maintain dimensional stability to width not much in excess of 12 to 24 inches. The present apparatus can be used with flaps up to 30 inches or more in width and it is ideally constructed for plating contours such as the epi-trochoid illustrated in FIGS. 4 and 5, ovals, U-shaped interiors, etc. While it is preferred to run the activator flaps submerged as illustrated in the drawings, the units can be operated with electrolyte sprays fed into a non-submerged plating zone should it be necessary or desirable for some reason. Several variations of supporting structures are shown and obviously a number of other constructions can be used in place of those illustrated. Drives can be by tension over drive pulleys only such as for structures illustrated in FIG. 1 or by positive engagement of the supporting structure with drive pulleys having geared or toothed surfaces, e.g. the structure of the support means illustrated in FIG. 3.

I claim:

1. In an electrodeposition apparatus adapted to have an anode, cathode and liquid electrolyte present in the plating zone, the combination comprising:
  - (a) means to position in a fixed location a contoured cathodic workpiece;
  - (b) a conforming, perforated pressure member closely spaced from said contoured workpiece and defining an open plating zone therebetween;
  - (c) driven supporting means parallel to and outboard from said so-defined open plating zone; and
  - (d) a plurality of hard particle supporting means affixed to and moved by said driven supporting means through said open plating zone in contact with said contoured workpiece and said pressure member within said plating zone.
2. Apparatus as in claim 1 wherein said conforming pressure member is an inert anode.
3. Apparatus as in claim 1 wherein said driven supporting means comprises a pair of parallel, flexible, spaced members.
4. Apparatus as in claim 3 wherein a plurality of cross members are affixed to and interconnect said parallel, flexible, spaced members.
5. Apparatus as in claim 1 wherein said hard particle supporting means comprise porous, open, resilient webs having a plurality of spaced hard particles affixed to at least the outer surface thereof.

6. Apparatus as in claim 5 wherein a plurality of rigid members affixed to said driven supporting means engage, support and move said webs carrying said hard particles as a plurality of flaps folded over each of said rigid members.

- 5 7. Electrodeposition apparatus comprising:
  - (a) a plating tank adapted to contain a liquid electrolyte;
  - (b) means to fix a workpiece having a two-dimensionally contoured surface to be plated within said tank;
  - (c) a pair of flexible supporting members adapted to be positioned in said tank adjacent each side of said workpiece and extending parallel with said contoured surface thereof;
  - (d) a plurality of flexible flaps of hard particle-carrying material affixed to and suspended between said flexible supporting members;
  - (e) means to move said flexible supporting members so as to contact said contoured surface with said hard particles on said flexible flaps;
  - (f) means to apply pressure to said flexible flaps as they pass over and in contact with said contoured surface; and
  - (g) means to apply an electrodeposition potential whereby said contoured surface receives electrodeposited metal ions while said flaps are passing thereover and in contact therewith.
- 10 8. Apparatus as in claim 7 wherein said means to apply pressure is a perforated anode.
- 15 9. Apparatus as in claim 7 wherein said hard particle-carrying material is a porous, resilient and fibrous web.
- 20 10. Apparatus as in claim 7 wherein said workpiece is an engine housing having interior contoured surfaces to be plated, such surfaces defining an epi-trochoid shape.
